UNITED STATES PATENT OFFICE.

HENRY G. CADY, OF PINE BLUFF, ARKANSAS.

WAGON-JACK.

No. 851,401.

Specification of Letters Patent.

Patented April 23, 1907.

Application filed September 17, 1906. Serial No. 334,866.

To all whom it may concern:

Be it known that I, HENRY G. CADY, a citizen of the United States, residing at Pine Bluff, in the county of Jefferson and State of Arkansas, have invented certain new and useful Improvements in Wagon-Jacks, of which the following is a specification, reference being had therein to the accompanying drawing.

10 My invention relates to improvements in wagon jacks, and has for its object, the provision of simple and effective means for lifting heavy weights, which will be inexpensive of production, easy of manipulation, and entirely practical in all respects.

15 With these and other objects in view, my invention consists of a fulcrum post, a supporting arm, an operating lever connecting the fulcrum block and supporting arm and adapted to raise the arm, an angular supporting block slidable upon the arm, and means for moving the block.

20 My invention further consists of a lifting jack embodying other novel features of construction, combination and arrangement of parts substantially as herein set forth.

25 Figure 1, is a side elevation of my improved wagon jack, in the first position as it is placed under the axle of a vehicle or any other object to be raised. Fig. 2, is a similar view of the same with the supporting block drawn up in position under the axle. Fig. 3, is a similar view of the device in the position of supporting the object. Fig. 4, is a perspective view of the lifting jack in the extended or non-supporting position. Fig. 5, is a longitudinal sectional view in perspective of the supporting block.

30 In the drawings: The numeral 1, designates the fulcrum post which is comparatively short and is preferably formed with a rounded upper end.

35 2, indicates the supporting bar formed with the lower inclined or pointed end 3, adapted to engage the base or support upon which the jack stands. An operating lever 4, is provided, to the lower end of which is secured the socket member or sleeve 5. This sleeve is rectangular in cross section and upon opposite sides thereof, are formed the two pairs of outstanding ears or lugs 6. The ends of the fulcrum post and supporting bar are each adapted to fit between the ears 6, of the sleeve, and bolts 7, are passed therethrough 50 to connect the members together.

55 Slidable upon the supporting bar, is a

block 8, having a longitudinal slot or opening 9, formed therethrough for the reception of the bar. This slot passes diagonally through the block so that the block stands out from the bar at an incline, and the lower corner of the opening is rounded as at 10, to engage the under side of the bar, and the diagonally opposite corner is beveled, as at 11. The block may also be formed with transverse 65 openings or slots 12, therein, which render it lighter, and form a better surface for gripping the object to be raised.

60 In order to facilitate the moving of the block upon the bar, I provide a wire or cord 13, which is fastened to the block at the lower end, passes along the upper side of the bar through a staple or eye 14, and is provided on the end, with a ring or suitable handle 15.

65 In operation, the supporting bar is placed under the object to be lifted, the fulcrum post and operating lever being in substantially vertical positions as shown in Fig. 1. The supporting block is then drawn up on the 80 supporting bar until it engages the object, as in Fig. 2. The operating lever is then pushed downward, thereby raising the supporting bar, the post serving as a fulcrum, shown in Fig. 3. The under side of the supporting bar rests upon the rounded upper 85 end of the fulcrum post and the parts will remain in this position until the operating lever is again raised.

70 From the foregoing description taken in connection with the drawings, it will be evident that I have accomplished all the objects herein set forth and have produced a practical and thoroughly efficient lifting jack.

I claim:

75 1. In a wagon jack, the combination with a fulcrum post, operating lever and supporting bar, of a block having a longitudinal slot therein to receive the supporting bar, said block having locking engagement upon the 100 supporting bar by reason of its fulcrumed arrangement thereupon.

2. In a wagon jack, the combination with a fulcrum post, operating lever and supporting bar, of a step block having a diagonally arranged slot therein so as to be slidably fulcrumed upon the supporting bar.

3. The combination with a fulcrum post and supporting bar connected by toggle joint, an operating lever, of a block slidable upon 110 the supporting bar and adapted to be frictionally locked thereon, and a flexible con-

nection for drawing the block upward on the supporting bar.

4. A wagon jack comprising a fulcrum post and supporting bar connected by toggle joint, 5 an operating lever secured to said toggle joint, a block having a longitudinally arranged slot therein provided with a beveled end to engage the supporting bar so as to be slidably fulcrumed upon the supporting bar,

and connections for drawing the block upward on the supporting bar.

In testimony whereof I affix my signature in presence of two witnesses.

HENRY G. CADY.
